UNITED STATES PATENT OFFICE.

HERMAN T. JARECKI AND GEORGE A. DISQUE, OF ERIE, PENNSYLVANIA.

DESIGN FOR A SPOON.

SPECIFICATION forming part of Design No. 20,897, dated June 30, 1891.

Application filed April 11, 1891. Serial No. 388,596. Term of patent 3½ years.

To all whom it may concern:

Be it known that we, HERMAN T. JARECKI and GEORGE A. DISQUE, citizens of the United States, residing at the city of Erie, in the 5 county of Erie and State of Pennsylvania, have invented and produced a new and original Design for Spoons; and we do hereby declare the following to be a full, clear, and exact description of the invention, such as will enable others skilled in the art to which it 10 pertains to make and use the same, reference being had to the accompanying drawing, and to the letters of reference marked thereon, forming part of this specification.

15 The figure is a view in elevation of a spoon embodying our design.

One of the leading features of our design for spoons consists in the handle of the spoon, which has a picture *in intaglio* or in bas-relief 20 thereon, illustrating a conventional block-house of olden time.

Another of the leading features of our design for spoons consists in the bowl of the spoon, which has on the inside thereof a picture *in intaglio* or in bas-relief of a naval engagement, representing, among other things, a small boat loaded with men in the foreground on its way from a ship shown at one 25 side of the picture to a ship shown in the distance at the opposite side of the picture.

30 In the accompanying drawings, showing our design, A is the upper portion of the handle of a spoon, the front of which is ornamented with a picture *in intaglio* or in bas-relief, the central feature of which is a block-house B, 35 having a flag-staff D thereon, from which a

flag E floats. At each side of said block-house field-guns C C are also shown in said picture, and the foreground F of the picture appears as a turfed lawn. The inside of the 40 bowl G of the spoon is ornamented with a picture *in intaglio* or in bas-relief, the central feature of which is a small boat J, loaded with men and supporting a flag L upon a foreground H of water, the stern I of a ship showing at one side of said picture, and a ship K 45 showing in the distance at the opposite side of said picture, toward which the bow of the small boat is directed, the said features, as shown and described, comprising our new and 50 original design for spoons. Therefore,

What we claim as new is—

The design for a spoon, substantially as shown, consisting of the handle thereof having a picture *in intaglio* or in bas-relief thereon 55 of a conventional block-house of olden time, and the bowl thereof having a picture *in intaglio* or in bas-relief therein of a naval engagement, the central feature of which is a small boat loaded with men in the foreground 60 on its way from the ship, the stern of which is shown at one side of the picture toward a ship shown in the distance at the opposite side of the picture, substantially as set forth.

In testimony whereof we affix our signatures 65 in presence of two witnesses.

HERMAN T. JARECKI.
GEORGE A. DISQUE.
